UNITED STATES PATENT OFFICE.

CHARLES J. DIEGES, OF NEW YORK, N. Y.

DESIGN FOR A BADGE.

44,363.

Specification for Design.

Patented July 22, 1913.

Application filed May 26, 1913. Serial No. 770,082. Term of patent 7 years.

To all whom it may concern:

Be it known that I, CHARLES J. DIEGES, a citizen of the United States, residing in the borough of Manhattan, city, county, and State of New York, have invented a new, original, and ornamental Design for a Badge, of which the following is a specification, reference being had to the accompanying drawing, forming a part thereof.

The figure represents an elevation of my new design.

I claim:

The ornamental design for a badge, as shown.

CHARLES J. DIEGES.

Witnesses:

W. B. BUSH,
D. W. GARDNER.
